PULLEY BLOCK

Filed June 13, 1923

2 Sheets-Sheet 2

Inventor:

Frederick B. Mallory,

Attorneys.

UNITED STATES PATENT OFFICE.

FREDERICK B. MALLORY, OF PORTLAND, OREGON.

PULLEY BLOCK.

Application filed June 13, 1923. Serial No. 645,110.

To all whom it may concern:

Be it known that I, FREDERICK B. MALLORY, a citizen of the United States of America, and resident of Portland, in the county 5 of Multnomah, in the State of Oregon, have invented certain new and useful Improvements in Pulley Blocks, of which the following is a specification, reference being had to the accompanying drawings.

10 My invention relates to devices such as pulley blocks and has for its main object the production of a block in which the sheave, running preferably on an axis fixed in the block-sides, is provided with means of lubrication adapted to functionate in any operative position which the block may assume in use.

15 Beside the main object my invention comprehends certain structural details which 20 possess in themselves distinct utility and, obviously, are not limited in their application to pulley blocks. What constitutes my invention will be hereinafter specified in detail and succinctly set forth in the appended 25 claims.

In the accompanying drawings,

Figure I is a medial vertical section partly in elevation of one of my blocks, with exception of the head for suspending it.

30 Figure II is a side elevation of the subject matter of Figure I, the same being partly in section indicated by line II—II in Figure I, and the sheave being partly broken away.

Figure III is a fragmental view showing 35 a section on the line III—III of Figure I.

Figure IV is a fragmental view showing in side elevation the means of connection between the axle and one block-side employed to prevent relative rotation between those 40 parts.

Referring to the numerals on the drawings, 1 indicates one block-side, and 2 the other. They are, when assembled, in preferred form of embodiment shown, firmly 45 united by an axle 3, in the present instance shown as the stationary or non-rotating type and upon which rotates a sheave 4 between the block-sides.

The block-sides are provided, respectively 50 with perforated ears 5, which represent any suitable members for securing thereto any usual or suitable head not necessary to illustrate, for completing and suspending or attaching the block.

55 In the preferred form of embodiment of

my invention illustrated the two block-sides are substantially identical in general outside contour, and are distinguished in details of interior construction mainly for the reason that, by preference, only one of them carries 60 means of lubrication for the bearing surfaces between the bushing 6 of the sheave hub and the axle.

Accordingly, the block-side 1 is provided on its inner side with two webs 7 and 8 65 which are disposed substantially at right angles thereto and parallel to each other, and which are united at their upper ends by a cross-web 9. At their lower ends they merge into two inturned webs 10 and 11 extending 70 towards each other from opposite ends of a segmental web 12. The webs 7, 8, 9, 10, 11, and 12 are closed preferably by being severally united to an all-embracing cover-wall 14, to which and to the outside shell of the 75 block-side the said webs serve, in effect, as truss supports.

Substantially at the lower extremities of the webs 7 and 8, I provide oppositely extending abutment webs 15 and 16 for a definite purpose to be presently described.

The wall 14 is preferably provided with a thickened annular boss 17, it being provided with an internally threaded aperture 18 for the reception of an externally threaded reduced terminal 19 of the axle 3. The terminal 19 projects through and is threaded into an aperture 20 in the outer wall of the block-side that is coaxial with the aperture 18 in the boss 17. The joint between the terminal 90 19 and the aperture 20 should be securely oil-tight, and is therefore preferably surrounded by a packing ring 23, which may be held in place by a groove in the base of lock-nut 24 which screws on the end of the 95 terminal 19.

The opposite edges of the webs 15 and 16 are for the purpose to be explained as aforesaid threaded to fit the threads of the terminal 19, with the effect, through their connection therewith, of dividing the space enclosed on one side by the cover-wall 14 into two entirely separated lubricant chambers which are designated for convenience of reference by the numerals 25 and 26, respectively.

The purpose of the said lubricant chambers is to afford independent means of lubrication to the bearings between the sheave and its axle. To that end I prefer to provide 110

two separate elongated chambers or bores 27 and 28 longitudinally disposed within the axle 3 and substantially parallel to its axis. The bore 27 communicates with the lubricant chamber 25 as through a radial port 29, and the bore 28 communicates with the lubricant chamber 26 as through a similar port 30. It will be noted that the axle is disposed at the ends of the chambers, so that irrespective of the amount of lubricant in each chamber, there will always be a flow to the sheave bearing. By disposing the webs 15 and 16 in different planes, as shown in Figure II, the axle being fixed irrevolvably in the assembled block, provision is made for constant independent communication between the bores 27 and 28 and their respective lubricant chambers. At the end of each of the ports 29 and 30 is provided, through curvatures 31 and 32 of the respective webs 7 and 8, a bay, designed and adapted to facilitate flow of lubricant into said ports, respectively.

The bore 27 is provided with means of lubricant flow therefrom, which consist preferably of a plurality of outlet ducts 35, discharging from the same side of the bore 27 as that on which the port 29 is located. In like manner, corresponding outlet ducts 36 on the opposite side of the axle 3 from that penetrated by the ducts 35 are provided for lubricant discharge from the bore 28. The open ends of the respective bores 27 and 28 are securely closed against oil leakage as by screw plugs 37. 38 and 39 indicate screw plugged filler vents for the lubricant chambers, respectively.

The block-side 2 is in outward appearance substantially identical with the block-side 1 to which in internal construction it conforms to some extent. If desired, the block-side 2 may be a duplicate of the side 1 both in form and function. It is, however, preferably provided with webs 40 of which one is shown in Figure I, which are substantially like the webs 7 and 8 but without the cover-wall 14 of the latter or other covering. The webs 40 serve as truss supports to the shell of the block-side as well as to a recessed axle support 41, which is provided therein for the guard of a nut 42 threaded to the reduced terminal 43. 44 indicates a base washer which is preferably provided for the nut 42 and which spans an aperture 45 provided in the end of the support 41 for reception of the terminal 43. The part 43 is provided at its base with an annular shoulder 46 which fits within an aperture provided for it in the end of the support 41, and which, being provided with flatted sides 47 (see Figure IV), presents an example of means for holding the axle 3 in place in the block against rotation, thereby fixing a definite relationship between the ports 29 and 30 and the abutment webs 15 and 16.

The operation of my device requires, in view of the preceding specification, only the following brief description.

The parts being assembled as shown in Figure I, with addition of means for suspension or attachment of the block indicated by the presence of the ears 5, and the lubricant chambers 25 and 26 being charged with a supply of fluid lubricant, the block is ready for use. The block may assume an indefinite number of positions in operation, particularly when employed for logging purposes for which it is especially designed and adapted. By provision of the lubricant chambers 25 and 26, substantially as they are described and illustrated, each being independent of the other, effective means of lubrication of the bearings of the block in any operative position are provided. Moreover, the entire separation of the lubricant chambers one from another insures against the result of draining the lubricant from one chamber into another, which would be often liable to occur if there were communication between them.

What I claim is:

1. A pulley block comprising the combination with a pair of block-sides, an axle supported thereby, and a sheave thereon, of wholly independent lubricating chambers in one of the block-sides, and separate means of communicating lubricant supply through the axle to the bearing surfaces of the sheave and axle, from one or the other of said lubricant chambers, depending upon the position occupied by the block in use.

2. A pulley block comprising the combination with a pair of block-sides, a fixed axle, and a sheave revolvable upon the axle, of independent lubricant chambers in one of the block-sides, a pair of separate longitudinal bores in the axle in operative communication with the bearing surfaces of the sheave and axle, and ports establishing operative communication between the said chambers and bores respectively.

3. A pulley block comprising the combination with a pair of block-sides, a fixed axle, and a sheave revolvable upon the axle, of independent lubricant chambers in one of the block-sides, a pair of separate longitudinal bores in the axle in operative communication with the bearing surfaces of the sheave and axle, and ports establishing operative communication between the said chambers and bores respectively, said lubricant chambers being provided with bays defined adjacent to the inlet ends of said ports substantially for the purpose specified.

4. A block-side provided with a pair of lubricant chambers defined in part by the wall of the shell of the block-side and a cover-wall for the chambers, the said walls being provided with coaxial threaded apertures and the said chambers being partly di-

vided by oppositely extending threaded abutment webs, said threaded apertures and webs being adapted to receive a threaded axle terminal with the effect thereby of completely separating the lubricant chambers one from the other.

5. In a device of the class described, a side plate having two independent lubricant chambers communicating respectively with an axle receiving space therebetween, said side plate having coaxial apertures between which said axle receiving space is located adapted to receive and support the extremity of an axle, and an axle inserted in said apertures and said space serving to receive lubricant from said chambers.

10. As an article of manufacture, an axle having means for transmitting lubricant longitudinally thereof and provided with a plurality of outlet ducts in connection with said means, said axle being formed with a plurality of inlet orifices leading to said means and disposed upon substantially opposite sides of the axle, said orifices being cut off 25 from communication with each other.

15. A pulley block comprising side plates, a sheave having an axle extending into said plates, at least two separated lubricant side reservoirs independent of the sheave and disposed on substantially opposite sides of the longitudinal axis of said axle, means for independently filling said reservoirs and means 30 communicating with each reservoir for transmitting lubricant from said reservoirs to the 35 sheave bearing.

20. A pulley block comprising side plates, a sheave having an axle extending into said plates, at least two separated and independent lubricant reservoirs disposed on substantially opposite sides of said axle in one of 40 said plates, means for independently filling said reservoirs and means communicating with each reservoir for transmitting lubricant from said reservoirs to the sheave bearing.

25. A pulley block comprising side plates, a sheave having an axle extending into said plates, at least two separated lubricant side reservoirs independent of the sheave and disposed on substantially opposite sides of the longitudinal axis of said axle, means 50 communicating with each reservoir for transmitting lubricant from said reservoirs to the sheave bearing, said means being located substantially at an end of each reservoir, and means for independently filling said reservoirs.

30. A pulley block comprising side plates, a sheave having an axle extending into said plates, at least two separated and independent lubricant reservoirs disposed on substantially opposite sides of said axle in one of 60 said plates, means communicating with each reservoir for transmitting lubricant from said reservoirs to the sheave bearing, said

means being located substantially at an end of each reservoir, and means for independently filling said reservoirs.

35. In a device of the class described, a support for an axle having two independent lubricant reservoirs, means for independently filling said reservoirs, each of the reservoirs having positioned in a plane between them a space adapted to receive an axle, and an axle fitted into said space, said reservoirs 70 each communicating with the axle and being arranged on substantially opposite sides of the longitudinal axis thereof.

40. In a device of the class described, a support for an axle having two independent lubricant reservoirs adapted to receive an axle therebetween, means for independently filling said reservoirs, the reservoirs having between them an axle, said reservoirs each 75 communicating with the axle and being arranged on substantially opposite sides of the longitudinal axis thereof.

45. In a device of the class described, a support for an axle having two independent lubricant reservoirs adapted to receive an axle therebetween, means for independently filling said reservoirs, the reservoirs having between them an axle, the axle serving to close off said reservoirs one from the other, and said reservoirs each communicating 80 with the axle and being arranged on substantially opposite sides thereof.

50. In a device of the class described, side plates at least one of which is provided with two independent lubricant reservoirs, a sheave axle fitted into said plate between said reservoirs, each of said reservoirs communicating with the axle, means for independently filling the reservoirs, said reservoirs being positioned on opposite sides of the longitudinal axis of said axle, means in 90 said axle for transmitting lubricant longitudinally thereof from the reservoirs, and inlet ports arranged on substantially opposite sides of the axle and communicating 95 with said reservoirs.

55. In a device of the class described, an axle having means for transmitting lubricant longitudinally thereof, and provided with a plurality of outlet ducts in connection with 100 said means, said axle being formed at one end with a pair of inlet orifices leading to said means and disposed upon substantially opposite sides of the axle, the orifices being 105 cut off from communication with each other.

60. In a device of the class described, an axle having means for transmitting lubricant longitudinally thereof, said axle being provided with outlet ducts for said lubricant 110 disposed intermediate the ends of said axle and a pair of inlet orifices communicating with said means disposed respectively upon substantially opposite sides of the longitudinal axis of the axle, and a support for said 115 axle having separated lubricant reservoirs 120

each in communication with one of said orifices.

17. In a device of the class described, an axle having means for transmitting lubricant longitudinally thereof, said axle being provided with outlet ducts for said lubricant disposed intermediate the ends of the axle and a pair of inlet orifices communicating with said means disposed respectively upon substantially opposite sides of the axle at one end thereof, and an axle support having separated lubricant reservoirs each in communication respectively with one of said orifices.

18. As an article of manufacture, an axle having means for transmitting lubricant longitudinally thereof and provided with a plurality of outlet ducts in communication with said means, said axle being formed with a plurality of inlet orifices leading to said means and circumferentially disposed upon substantially opposite sides of the axle, said orifices being cut off from communication with each other.

In testimony whereof, I have hereunto set my hand.

FREDERICK B. MALLORY.
